ELECTRIC ARC FURNACE

Hugo L. Kuehlthau, Chicago, Charles W. Vokac, Cicero, and Michael Del Monte, La Grange, Ill., assignors to Whiting Corporation, Harvey, Ill., a corporation of Illinois

Application May 17, 1944, Serial No. 535,930

20 Claims. (Cl. 13—10)

The present invention relates generally to electric arc furnaces for use in metallurgy. More particularly the invention relates to that type of electric arc furnace which is known in the art as a "top charge" furnace and as its main or principal component parts comprises: (1) an open top shell which is adapted to be charged through the top thereof with metallic material to be processed or reduced to molten form, has a lining of refractory material and in addition a side spout for discharging the molten metal, and is mounted so that it is tiltable back and forth between a normal upstanding position and an inclined pouring position wherein the side spout extends downwards; (2) a refractory lined roof which normally rests on the top portion of the lining of the shell where it serves as a closure for the shell in connection with a metal melting operation and is pivotally supported so that it may be swung laterally to one side of the shell into an open position wherein the top of the shell is exposed for charging purposes; (3) a plurality of upstanding electrodes which extend slidably through holes in the central portion of the roof and are provided with means for supplying them with electric current; and (4) a plurality of electrode supporting members which are associated respectively with, and correspond in number to, the electrodes and consist of horizontally extending cantilever type arms having clamps at their outer ends for the upper ends of the electrodes, and vertical extensions which are connected to the inner ends of, and depend from, the arms and are slidably mounted so that the members may be shifted in order to effect raising and lowering of the electrodes with respect to the shell.

In an electric arc furnace of this type it has heretofore been proposed to utilize as a mount for the roof a laterally extending bracket on the roof and a shaft which depends from the bracket, fits slidably and rotatably in a tubular member on the side wall of the shell and permits the roof to be raised preparatory to being swung laterally into its open position and also to be lowered onto the upper portion of the lining of the shell after it has been swung back into overlying relation with the shell. It has also been proposed to mount the electrode supporting members on the bracket of the mount for the roof in order that they, together with the electrodes, tilt with the roof and shell in connection with a molten metal pouring or discharging operation and also swing laterally to one side of the shell when the roof is swung into its open position wherein the

top of the shell is exposed for charging purposes. In practice it has been found that an electric arc furnace wherein the roof has a mount of the aforementioned character and the electrode supporting members are mounted on the bracket of the mount, is subject to certain objections. In the first place when the roof is in its operative position wherein it rests on the top portion of the refractory lining of the shell the shell lining is subjected to not only the weight of the roof but also the weight of the electrodes, the electrode supporting members, the laterally extending bracket, and the shaft and hence has but a short life and must be replaced at frequent intervals. Secondly, when the roof is in its operative or closed position the refractory shell lining is subjected to unequal downward pressure due to the fact that the electrode supporting members are connected to the bracket of the mount which is laterally offset with respect to the axis or center of the shell.

The primary object of the invention is to provide an electric arc furnace which is an improvement upon, and eliminates the disadvantages or 25 deflections of, previously designed furnaces of the same general type and is characterized by the fact that it includes a bracket structure which is pivotally connected to the shell so that it is only capable of swinging laterally, serves to support the electrode supporting members, and has means whereby the roof is suspended so that it may be independently raised preparatory to being swung laterally into its open position and also independently lowered onto the top portion of the 35 shell lining after it is swung back into overlying relation with the shell following a shell charging operation. By providing the bracket structure and utilizing the roof suspension means the refractory lining of the shell is subjected to only 40 the weight of the roof when the roof is in its operative or closed position and the downward pressure which is exerted on the shell lining by the roof is uniform or equal and hence the life of the shell lining is materially increased and it 45 is resultantly not necessary to replace the shell lining at frequent intervals.

Another object of the invention is to provide an electric arc furnace of the last mentioned type and character in which the suspension 50 means for raising and lowering the roof with respect to the shell is of simple and novel design, and the bracket structure embodies novel mounting means for the electrode supporting members and has simple power means whereby it may be 55 swung laterally away from the shell in connection

with shift of the roof into its open position and also swung laterally toward the shell in connection with return movement of the roof into overlying relation with the shell.

A further object of the invention is to provide an electric arc furnace which is generally of new and improved construction, effectively and efficiently fulfills its intended purpose and is characterized by simplicity of design and long life.

Other objects of the invention and the various advantages and characteristics of the present electric arc furnace will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a side view of an electric arc furnace embodying the invention, illustrating in detail the construction, design and arrangement of the bracket structure which is pivotally connected to the shell for lateral swinging movement, serves to support the electrode supporting members and has associated therewith roof suspension means whereby the roof may be raised and lowered relatively thereto out of and into its closed position with respect to the shell;

Figure 2 is a side view of the furnace taken at right angles to Figure 1 and showing the manner in which the receptacle is mounted so that it is tilttable back and forth between a normal upstanding position and an inclined pouring position wherein the side spout extends downwards;

Figure 3 is a plan view of the furnace illustrating the manner in which the bracket structure is capable of being swung laterally away from the shell in order to shift the roof into its open position and also laterally toward the shell in order to bring the roof into overlying relation with the shell after a shell charging operation;

Figure 4 is a vertical section taken on the line 4—4 of Figure 2 and showing in detail the manner in which the vertical extensions of the electrode supporting members are slidably mounted with respect to the bracket structure;

Figure 5 is a fragmentary side view of the furnace with certain parts thereof broken away and other parts thereof shown in section in order to illustrate in detail the suspension means for effecting raising and lowering of the roof relatively to the bracket structure and the shell;

Fig. 5a is an enlarged section of one of the removable connections between the roof suspension means and the roof; and

Figure 6 is an enlarged horizontal section on the line 6—6 of Figure 2.

The electric arc furnace which is shown in the drawings constitutes the preferred form or embodiment of the invention. It is of the so-called "top charge" variety and serves as a medium or instrumentality for processing or reducing to molten form metallic material. As its main or principal parts the furnace comprises a shell 10, a roof 11, a bracket structure 12, suspension means 13 for raising and lowering the roof relatively to the bracket structure, a plurality of upstanding electrodes 14, and a plurality of electrode supporting members 15.

Shell

The shell 10 has an open top whereby it may

be charged with the metallic material to be processed or reduced to molten form, and comprises a cylindrical side wall 16 and a downwardly dished or bulged bottom 17. It also comprises a lining 18 of refractory material and has a discharge spout 19 and a slag door 20. The side and bottom walls are formed of heavy plate metal and are welded or otherwise fixedly secured together. The upper margin of the side wall 16 is reinforced by an angle bar type ring 21. The spout 19 and the slag door 20 are mounted on the side wall 16 of the shell and are preferably positioned one diametrically opposite the other. As shown in Figure 4, the refractory lining 18 covers the inner surfaces of the side and bottom walls of the shell and is cup shaped. The upper or top portion of the refractory lining 18 projects a slight distance above the reinforcing ring 21 around the upper margin of the shell side wall 16. The shell is mounted by way of a pair of gear segments 22 and a pair of racks 23 so that it may be tilted back and forth between a normal upstanding position and an inclined pouring position wherein the spout 19 extends or projects downwards. The gear segments 22 are disposed in laterally spaced, parallel relation and underlie and are welded or otherwise fixedly secured to the bottom wall 17 of the shell 10. They rest upon, and mesh with, the racks 23. The latter are mounted on the foundation over which the furnace is disposed. When the shell 10 is urged in the direction of the spout 19 it tilts, as shown by dotted lines in Figure 2, into a position wherein the spout 19 extends downwards and serves to discharge the molten metal in the shell. When the shell is urged in the reverse direction it tilts upward into its normal upstanding position. The shell is tilted or rocked back and forth between its pouring and normal positions by conventional or standard power actuated mechanism (not shown). It is contemplated that the shell will be charged while in its normal upstanding position and will be retained in such position until the charge is reduced to molten form by the heat which is generated as the result of the supply of current to the electrodes 14. After the charge is melted or processed to the desired extent the shell is tilted so as to effect discharge of the molten metal via the spout 19.

50

Roof

The roof 11 is mounted, as hereinafter described, so as to swing laterally back and forth between a normal or operative position wherein it overlies and seals the shell and an open or inoperative position wherein it is disposed at one side of the shell and exposes the top of the shell for charging purposes. It is substantially the same in diameter as the side wall 16 of the shell 10 and comprises an upwardly bulged circular or disc-like lining 25 of refractory material, and a metallic annulus 26. As shown in Figure 4, the annulus 26 is channel shaped in cross section and has the flanges thereof extending inwards. The margin of the refractory lining 25 rests upon the lower flange of the annulus 26. The lining 25 is of substantial thickness and when the roof is in its closed or operative position, forms with the lining 18 of the shell 10 a substantially closed or sealed chamber 27 for the charge of metallic material to be reduced to molten form. The margin of the lining 25 of the roof 11 is adapted to rest on the top or projecting portion of the lining 18 of the shell 10. It is contemplated during use of the furnace that in connection with a shell charg-

75

ing operation the roof 11 will first be raised to a slight extent so as to disengage the lining 25 from the lining 18. Thereafter the roof will be swung laterally to one side of the shell so as to expose the open top of the shell for introduction of the charge of material. After the material is introduced into the shell the roof 11 is swung back into overlying relation with the shell and is then lowered so as to bring the flat bottom surface of the marginal portion of the roof lining 25 into abutment or seated relation with the top of the shell lining 18.

Bracket structure

The bracket structure 12 carries the roof suspension means 13 and the electrode supporting members 15 and is hinged or pivotally connected to the shell so that it is capable of being swung laterally away from the shell in order to shift the roof into its open position and also laterally toward the shell in order to bring the roof into overlying relation with the shell after a shell charging operation. It comprises an arm 28, a plate 29 and a U-shaped frame 30. The arm 28 is preferably formed of cast metal and extends horizontally when the shell 10 is in its normal upstanding position wherein the axis thereof is truly vertical. It is vertically and horizontally elongated and embodies at one end thereof an integral upstanding tubular part 31. A rectangular plate 32 extends across, and is welded or otherwise fixedly secured to, the upper end of the tubular part 31 and forms a closure cap for said part. In addition to the tubular part 31 the arm embodies an outwardly extending top flange 33, an outwardly extending bottom flange 34, and an outwardly extending end flange 35. Such flanges are formed integrally with the arm and serve, together with a pair of upstanding webs 36, to stiffen or reinforce the arm as a whole. The end flange 35 is located at the distal end of the arm 28 and has its ends joined to the adjacent ends of the top and bottom flanges 33 and 34. The webs 36 are formed integrally with the outer surface portion of the arm 28 and have the upper ends thereof joined to the central portion of the top flange 33 and their lower ends joined to the central portion of the bottom flange 34. As shown in Figures 1 and 2, the tubular part 31 of the arm 28 surrounds and is mounted rotatably on the upper end of an upstanding shaft 37. The lower end of such shaft is carried by a vertically extending bracket 38 on the side wall 16 of the shell 10. The bracket 38 is preferably in the form of a metallic casting and projects laterally from the side wall of the shell. It embodies at its inner portion an upstanding arcuate wall 39 which, as shown in Figure 6, is curved conformably to the shell side wall 16 and is welded or otherwise fixedly secured in place. The outer portion of the bracket 38 is provided with integral semicircular parts 40 and these are spaced vertically apart and extend normally horizontally and have outwardly extending integral lugs 41 at their ends. The lower end of the shaft 37 is seated in the semicircular parts 40 and is clamped in place by way of a pair of semicircular clamping members 42. The latter are associated, respectively with, and are arranged in opposed relation with respect to, the semicircular parts 40 of the bracket 38 and have outwardly extending end lugs 43. Bolts 44 extend through the lugs 41 and 43 and serve to clamp the members 42 and thus lock or fix the lower end of the shaft 37 to the bracket 38. The bracket 38 is so arranged that it operates to space

the shaft 37 a slight distance from the shell 10 and also to hold the shaft so that the axis thereof is in true parallel relation with the axis of the shell. A pin 45 extends through the tubular part 31 of the arm 28 and into an annular groove 46 in the upper end of the shaft 37 and serves to hold the tubular part against axial displacement with respect to the shaft while at the same time permitting the arm to swing laterally to and from the furnace shell 10.

The plate 29 of the bracket structure 12 extends vertically and is rectangular so far as shape or contour is concerned. It is disposed inwards of the inner face of the arm 28 and is arranged in parallel relation with the arm. Pairs of upstanding cross plates 47 extend between the arm 28 and the plate 29 and serve to hold the latter in rigid connected relation. As shown in Figure 6, the cross plates of each pair are spaced laterally apart to define between them an upstanding slideway 48. The outer end edges of the cross plates 47 abut against, and are welded to, the inner face of the arm 28 and the inner end edges of said cross plates abut against, and are welded to, the outer face of the plate 29. The upper margin of the plate 29 is reinforced by a longitudinally extending I-beam 49 and this is disposed inwards of the plate and has the inner edges of its top and bottom flanges welded to the upper portion of the inner face of the plate 29. As shown in Figure 1, the I-beam 49 is positioned so that the top flange thereof is flush with the upper edge of said plate 29. A pair of normally horizontal plates 50 overlie, and are welded to, the ends of the top flange of the I-beam 49 (see Figure 3).

The U-shaped frame 30 of the bracket structure 12 projects inwards from the arm 28 and the plate 29 and overlies, and is spaced above, the roof 11. It extends horizontally when the shell 10 is in its normal or upstanding position and consists of a pair of parallel laterally spaced side legs 51 and a cross leg 52. These three legs are formed of tubular metal stock of rectangular cross section in order that the frame 30 as a whole is hollow and hence may have water or any other coolant circulated therethrough for cooling purposes. The ends of the cross leg 52 of the frame 30 are suitably connected to the ends of the side legs that are farther from the arm 28. The other ends of the side legs, i. e., the ends that are nearer the arm 28, rest on, and are welded to, the plates 50 at the ends of the I-beam 49. The inner end of one of the side legs 51 of the frame 30 is closed by a plate 53 having a nipple 54 for attachment to a flexible water supply tube 55. The inner end of the other side leg of the frame is closed by a plate 56 having a nipple 57 for attachment to a flexible water discharge tube 58. The legs of the frame 30 are so arranged that the water which is introduced via the nipple 54 circulates first through said one side leg, then through the cross leg 52 and then through the other side leg to the nipple 57.

The bracket structure 12 is swung laterally away from and towards the shell 10 for roof positioning purposes by means of power means comprising a piston-cylinder device 59. The latter, as best shown in Figure 6, is positioned adjacent the upper end of the shaft carrying or supporting bracket 38 and consists of a cylinder 60 and a piston 61. The cylinder 60 extends horizontally when the shell 10 is in its normal upstanding position and has an end wall 62 at one end thereof and an end wall 63 at its other end. The end wall 62 of the cylinder is provided with an externally

disposed U-shaped lug 64 which straddles a horizontally extending lug 65 and is pivotally connected thereto by way of a pin 66. The lug 65, as shown in Figure 6, is welded to the upstanding arcuate wall 39 at the inner portion of the bracket 38. The pivot pin 66 permits the piston-cylinder device 59 to swing laterally. The piston 61 is slidably mounted in the cylinder 60 and is provided with a piston rod 67 which extends through, and is slidably mounted in, a stuffing box 68 on the end wall 63 of the cylinder. The inner end of the piston rod is fixedly connected to the piston and the outer end of the rod is provided with a U-shaped lug 69 which straddles a laterally extending normally horizontal lug 70 on the lower end of the tubular part 31 of the arm 28 and is pivotally connected to said lug 70 by a normally vertically extending pin 71. The lug 70 is welded or otherwise fixedly secured to the lower end of the tubular part 31 and is so arranged with respect to the lug 65 that the piston-cylinder device 59 is not in dead center relation with the shaft 31. The cylinder 60 is provided at its ends with nipples 72 and 73 whereby fluid under pressure may be introduced into it. The nipple 72 is disposed adjacent the end wall 62 and the nipple 73, as shown in Figure 6, is disposed adjacent the end wall 63. When fluid under pressure is introduced into the cylinder via the nipple 72 while the nipple 73 is vented the piston 61 is forced towards the cylinder end wall 63 and operates through the medium of the piston rod 67 and the laterally extending lug 70 on the tubular part 31 of the arm 28, to swing the bracket structure 12 laterally away from the shell 10. When fluid under pressure is introduced into the cylinder via the nipple 73 while the nipple 72 is vented or open to atmosphere the piston 61 is forced toward the cylinder end wall 62 and operates through the medium of the piston rod 67, the lug 70 and the tubular part 31, to swing the bracket structure laterally toward the furnace shell 10. The stroke of the piston 61 is such that when the piston is in abutment with the cylinder end wall 62 the bracket structure is disposed wholly out of overlying relation with the shell, as shown by dotted lines in Figure 3, and when the piston is in abutment with the cylinder end wall 62 the frame 30 of the bracket structure is in direct overlying relation with the shell, as shown by full lines in Figure 3. The piston-cylinder device 59 constitutes simple means for swinging the bracket structure 12 to and from the shell 10 in connection with shift of the roof 11 into and out of its normal or operative position. In a small sized furnace a hand lever or other manually operated means (not shown) may be substituted for the piston-cylinder device 59.

Roof suspension means

The roof suspension means 13 serves as a medium for supporting the roof so that it is capable of being raised and lowered relatively to the bracket structure 12. It is mounted on the bracket structure and comprises a plurality of flexible elements in the form of chains 74. The latter are shown in the drawings as being four in number and are associated respectively with, and depend from, the ends of the side legs 51 of the U-shaped frame 30 of the bracket structure. The lower ends of the chains are connected by cross pins 75 to the upper ends of upstanding pipe sections 76. Said cross pins extend through the lowermost links of the chains and have the ends thereof disposed in holes in the upper ends of the pipe sections 76. The lower

ends of the pipe sections 76 are removably connected to the metallic annulus 26 of the roof 11 by way of upstanding stub shafts 76^a and wedge shaped keys 76^b (see Figure 5^a). The upper ends of the stub shafts fit snugly within, and are welded to, the lower ends of the pipe sections 76. The lower ends of said stub shafts are of reduced diameter, extend through holes 76^c in the top flange of the annulus 26 and fit removably in sleeves 76^d. The latter are disposed beneath, and have the upper ends thereof welded to, the top flange of the annulus 26 and are in registering relation or alignment with the holes 76^c. The wedge shaped keys 76^b extend through slots 76^e in the web of the annulus 26 and have the inner ends thereof disposed in aligned slots in the sleeves 76^d and the lower ends of the stub shafts 76^a. When the keys 76^b are driven inwards into their normal or operative position they wedge the stub shafts 76^a downwards so that the enlarged upper ends thereof are clamped against the upper surface of the top flange of the annulus 26. By reason of the fact that the lower ends of the pipe sections 76 are removably connected to the annulus of the roof the roof may be released from the suspension means when it is desired to replace it. In connection with replacement of the roof it is only necessary to withdraw the wedge shaped keys 76^b and then swing the bracket structure 12 away from the shell 10. Upon shift of the bracket structure away from the shell the roof is exposed and hence may be removed by an overhead crane or the like and a new roof substituted for it. The central portions of the chains 74 extend through upstanding pipe sections 77 adjacent the ends of the side arms 51 of the frame 30. As shown in Figure 5, the pipe sections 77 are of greater diameter than the pipe sections 76 and have the lower ends thereof in loose telescopic relation with said pipe sections 76. By reason of the fact that the lower ends of the pipe sections 77 are in telescopic relation with the pipe sections 76 the roof 11 is permitted to move vertically to and from the frame 30 of the bracket structure while at the same time it is held against lateral displacement relatively to the frame. The upper ends of the pipe sections 77 extend through, and are welded to, the ends of the side legs 51 of the U-shaped frame 30. The upper ends of the chains 74 are trained around sector shaped sheaves 78 and are anchored to the upper portions of the latter by way of eye-bolts 79. The sheaves are mounted on stub axles 80 which are carried respectively by pairs of triangular bracket plates 81. The bracket plates, as shown in Figure 5, are welded to, and project upwards from, the side portions of the side legs 51 of the U-shaped frame 30. The upper portions of the bracket plates are provided with holes in which the ends of the stub axles 80 are mounted. The eyes of the eye-bolts 79 are connected to the upper end links of the chains 74 and the shanks of the bolts extend through apertured cross webs 82 on the upper portions of the sheaves and have nuts 83. The latter abut against the aperture defining portions of the cross webs 82 and constitute means whereby the chains 74 may be adjusted with respect to the sheaves. When the nuts 83 are tightened the chains are drawn upwards with respect to the sheaves and when the nuts are loosened the chains are downwardly paid out relatively to the sheaves. By properly adjusting the nuts the chains 74 may be so positioned with respect to the sheaves that they hold the roof 11 in a truly

horizontal position when it is raised prior to being swung laterally into its open position. When the sheaves 78 are rotated in a clockwise direction as viewed in Figure 5, i. e., so that they wind up the chains 74, the roof is raised. When the sheaves are reversely rotated the chains are paid out and result in lowering of the roof relatively to the U-shaped frame 30 of the bracket structure 12.

The sheaves 78 are conjointly turned for roof raising or lowering purposes by power mechanism which constitutes part of the suspension means 13 for the roof 11 and comprises an upstanding cylinder-piston device 84, an arm 85, a normally horizontal rock shaft 86, a pair of arms 87, a pair of links 88, a pair of bell cranks 89 and a pair of links 90. The upstanding cylinder-piston device 84 consists of a cylinder 91 and a piston 92 and is located directly outwards of the arm 28 of the bracket structure 12. The lower end of the cylinder 91 is provided with an end wall 93 and the upper end of the cylinder is provided with an end wall 94. The end wall 93 embodies an external U-shaped lug 95 which straddles a lug 96 and is pivotally connected to the latter by a pin 97. The lug 96 projects forwards from, and is formed integrally with, the central portion of the bottom flange 34 of the arm 28. The pin 97 extends through registering holes in the lugs 95 and 96 and permits the cylinder-piston device 84 to swing to and from the arm 28. The piston 92 is slidably mounted in the cylinder 91 and is provided with a piston rod 98 which extends through and is slidably mounted in a stuffing box on the end wall 94 of the cylinder 91. The inner or lower end of the piston rod is fixedly connected to the piston 92 and the outer or upper end of the rod is provided with a U-shaped lug 99. The cylinder 91 of the cylinder-piston device 84 is adapted to receive fluid under pressure for piston operating purposes by way of nipples 100 and 101 at its ends. The nipple 100 is located immediately adjacent the end wall 93 and the nipple 101 is located directly beneath the end wall 94. When fluid under pressure is introduced into the cylinder via the nipple 100 while the nipple 101 is vented the piston 92 is forced upwards towards the cylinder end wall 94. When fluid under pressure is introduced into the upper end of the cylinder via the nipple 101 while the nipple 100 is vented the piston 92 is forced downwards towards the cylinder end wall 93. The U-shaped lug 99 at the upper end of the piston rod 98 surrounds one end of the arm 85 and is pivotally connected thereto by a pivot pin 102. The other end of the arm 85 is fixedly connected to the central portion of the rock shaft 86. As shown in Figure 2 the rock shaft is located directly outwards of the upper portion of the arm 28 and has its ends journalled in bearings 103 on the upper corner portions of the arm 28. When the piston 92 is forced upwards as heretofore pointed out, the arm 85 operates to turn the rock shaft 86 in a counterclockwise direction as viewed in Figure 1 and when the piston 92 is forced downwards the arm 85 operates to turn or rock the shaft 86 in a clockwise direction as viewed in Figure 1. In a small sized furnace a hand lever or other suitable manually actuated means (not shown) may be used to rock the shaft 86 for roof raising and lowering purposes instead of the piston-cylinder device 74. The arms 87 are fixedly connected to, and project outwardly from, the ends of the rock shaft 86 as shown in Figure 2. The links 88 are disposed in an upstanding position

and are aligned with the side legs 51 of the U-shaped frame 30. The lower ends of the links 88 are pivotally connected to the outer or distal ends of the arms 87. The bell cranks 89 comprise outwardly extending arms 104 and upwardly extending arms 105 and have the central portions thereof connected by pins 106 to brackets 107 on the upper corners of the arm 28 of the bracket structure 12. The pins 106 are so arranged that the bell cranks 89 are permitted to swing in vertical planes when the shell 10 is in its normal upstanding position. The upper ends of the links 88 are pivotally connected to the outer or distal ends of the upwardly extending arms 104 of the bell cranks 89. The links 90 are disposed above and in parallel relation with the side legs 51 of the U-shaped frame 30. The ends of the links 90 that are disposed adjacent the arm 28 are pivotally connected to the outer or distal ends of the arms 105 of the bell cranks 89. The portions of the links 90 that are adjacent the sector shaped sheaves 78 are pivotally connected by pins 108 to upstanding lugs 109 on the upper portions of the sheaves. When the piston 92 of the piston-cylinder device 84 is forced downwards by introducing fluid under pressure into the upper end of the cylinder 91 via the nipple 100 the rock shaft 86 is caused to rock in a clockwise direction as viewed in Figure 1 and operates through the medium of the arms 87 and the links 88 to rock or swing the bell cranks 89 in a clockwise direction as viewed in Figure 1. Such swinging of the bell cranks operates through the medium of the links 90 to turn the sheaves 78 in a clockwise direction as viewed in Figures 1 and 5 and results in raising of the roof 11 with respect to the shell 10. When the roof is in its raised position it may be shifted laterally into its open position by swinging the bracket structure 12 through the medium of the piston-cylinder device 59. As heretofore pointed out, the roof when in its open or inoperative position exposes the shell so that it may be charged with a batch of metallic material to be processed or reduced to molten form. After charging of the shell the roof is returned to overlying relation with the shell by reverse swinging of the bracket structure 12 through the medium of the cylinder-piston device 59. After the roof is shifted into overlying relation with the shell it is lowered into its closed or operative position by introducing fluid under pressure into the lower end of the cylinder 91 via the nipple 100 and venting the nipple 101. As soon as fluid under pressure is introduced into the lower end of the cylinder 91 the piston 92 is forced upwards and, as previously pointed out, operates through the medium of the arm 85 to rock the rock shaft 86 in a counterclockwise direction as viewed in Figure 1. Such rocking on the part of the rock shaft operates through the medium of the arms 87 and the links 88 to rock the bell cranks 89 in a counterclockwise direction and such rocking on the part of the bell cranks operates through the medium of the links 90 to turn the sheaves 78 in a counterclockwise direction as viewed in Figures 1 and 5 and resultantly to pay out the chains 74 and effect lowering of the roof. When the roof is in its closed position its weight alone is imposed on the refractory lining 27 of the shell 10 and hence the lining 27 is subjected to a minimum amount of downward pressure and its life is thereby materially increased. By providing the roof suspension means 13 the weight of the bracket structure 12, the electrodes and the elec-

trode supporting members is not imposed upon the lining of the shell when the shell is in its closed or operative position. Another advantage of utilizing the specific roof suspension means 13 resides in the fact that the downward pressure which is exerted by the roof on the shell lining is uniform or equal. In other words, when the roof is in its closed position the top portion of the shell lining 27 is subjected to uniform downward pressure with the result that the side portion of the lining deteriorates uniformly and it is not necessary to replace the shell lining at frequent intervals.

Electrodes

The electrodes 14 are arranged in an upstanding position and extend slidably through holes 110 in the central portion of the refractory lined roof 11. They are supplied with electric current and serve, when the furnace is in operation, to produce electric arcs, the heat of which operates to reduce to molten form the charge of metallic material in the chamber 27. In the drawings three electrodes are illustrated. It is to be understood, however, that a lesser or greater number of electrodes may be employed, depending upon the size or capacity of the furnace. Normally the electrodes are positioned so that the lower ends thereof project into the chamber 27. When it is desired to charge the shell 10 the electrodes are raised so that the lower ends thereof are positioned above the top portion of the lining 18 of the shell. When the electrodes are raised to such an extent the roof 11 may be swung laterally into its open position by swinging the bracket structure 12 away from the shell as heretofore described.

Electrode supporting members

The electrode supporting members 15 are associated respectively with, and correspond in number to, the electrodes 14 and consist of normally horizontal cantilever type arms 111 and normally vertical extensions 112. The outer ends of the arms 111 are provided with clamping devices 113, which surround the upper ends of the electrodes 14 and serve releasably to connect the electrodes to the arms. The inner ends of the arms 111, i. e., the ends that are remote from the clamping devices 113, overlie, and are bolted to, plates 114 on the upper ends of the vertical extensions 112 of the electrode supporting members 15. Said extensions 112 are hollow and have open lower ends. They extend through, and are slidably mounted in, the slideways 48 between the cross plates 47 so that the supporting members 15 are capable of being shifted in order to effect lowering and raising of the electrodes with respect to the shell 10. As shown in Figure 6, the cross plates 47 are provided with rollers 115 which are disposed in the slideways 48, engage the end walls of the vertical extensions and serve slidably to support the extensions for vertical sliding movement with respect to the slideways. By reason of the fact that the cross plates 47 which define the slideways 48 for the vertical extensions of the electrode supporting arms constitute a part of the bracket structure 12 and are rigidly connected to the arm 28, the electrode supporting members, together with the electrodes, swing conjointly with the bracket structure and roof in connection with shift thereof away from and to the shell 10. The electrode supporting members 15 are raised and lowered by way of piston-cylinder devices 116. These devices con-

sist of cylinders 117 and pistons 118 and extend lengthwise of, and are partially disposed in, the vertical extensions 112. The lower ends of the cylinders 117 rest upon the bottom parts of U-shaped stirups 119. The upper ends of the side parts of such stirups are welded or otherwise firmly secured to the lower portions of the cross plates 47. The pistons 118 are slidably mounted in the cylinder 117. As shown in Figure 4, the upper ends of the pistons extend through stuffing boxes 120 at the upper ends of the cylinders 117 and abut against the plates 114 at the upper ends of the vertical extensions 112. The lower ends of the cylinders are provided with ports 121 whereby fluid under pressure may be introduced therein or withdrawn therefrom. When fluid under pressure is introduced into the lower ends of the cylinders the pistons are forced upwards and cause raising of the electrodes. Withdrawal of fluid from the lower ends of the cylinders 117 results in downward shift of the pistons and resultant lowering of the electrodes. In connection with operation of the furnace the flow of fluid under pressure to and from the lower ends of the cylinders is automatically controlled so as to effect the proper feed of the electrodes with respect to the shell 10.

Operation

When it is desired to use the furnace the electrodes 14 are first raised until their lower ends are above the top portion of the refractory lining 18 of the shell 10. Thereafter the roof 11 is raised relatively to the bracket structure 12. As heretofore pointed out, raising of the roof is effected by introducing fluid under pressure into the nipple 101 so as to force downwards the piston 92 of the cylinder-piston device 84. Downward movement of the piston results in turning of the sector shaped sheaves 78 in a clockwise direction as viewed in Figures 1 and 5, and resultant raising of the roof. As soon as the roof is raised so that it is clear or free of the top portion of the lining 18 of the shell the cylinder-piston device 59 is operated so as to swing the bracket structure 12 laterally away from the shell 10. As soon as the bracket structure is swung to its fullest extent away from the shell the roof 11 exposes the open top of the shell so that the shell may be charged with the metallic material to be reduced to molten form. After charging of the shell the bracket structure 12 is swung back into its normal position wherein the U-shaped frame 30 and the roof 11 overlie the shell. Return swinging of the bracket structure is effected by introducing fluid under pressure into the outer end of the cylinder 60 via the nipple 72 and venting the nipple 72. After return of the bracket structure to its normal position the roof 11 is lowered into sealed relation with the top portion of the refractory lining 18 of the shell. Lowering of the roof is effected by introducing fluid under pressure into the lower end of the cylinder 91 via the nipple 100 and venting the nipple 101. After lowering of the roof the electrodes 14 are shifted downwards until the lower ends thereof are in proper position with respect to the charge of material in the chamber 27. As soon as the electrodes are in place current is supplied to them so as to produce the necessary heat to reduce the material to molten form. As soon as the charge of material is melted the shell 10 with the roof in place thereon is tilted so as to effect discharge of the molten metal via the spout 19. At the conclusion of the pouring op-

eration the shell is tilted back to its normally upstanding position.

The herein described electric arc furnace effectively and efficiently fulfills its intended purpose and requires infrequent replacement of the refractory lining of the shell by reason of the fact that the roof is suspended for raising and lowering relatively to the bracket structure and hence when in its operative or closed position its weight only is imposed on the lining of the shell. Because of the design, construction and arrangement of the suspension means for the roof but a small amount of time is required to effect charging of the shell and the operating cycle of the furnace may be carried out with such great rapidity that the furnace is capable of melting a maximum amount of metallic material.

The invention is not to be understood as restricted to the details set forth since these may be modified within the scope of the appended claims without departing from the spirit and scope of the invention.

Having thus described the invention what we claim as new and desire to secure by Letters Patent is:

1. An electric arc furnace comprising a shell having a discharge spout at the side thereof and mounted so that it may be tilted for discharge purposes, a bracket structure having a frame part that is horizontally disposed when the shell is vertically positioned, and connected to the shell so that it is movable sidewise back and forth between a position wherein the frame part overlies the shell and a position wherein said frame part is disposed at one side of the shell, a roof for the shell located beneath the frame part of the bracket structure and provided with a hole therethrough, means mounted on the bracket structure and arranged and adapted to raise and lower the roof relatively to said frame part and also connect the roof to said structure so that it is movable sidewise therewith, an electrode extending normally through the hole in the roof, and supporting means for the electrode carried by said bracket structure and independent of the first mentioned means.

2. An electric arc furnace of the "top charge" variety comprising a tiltable shell, a bracket structure having a frame part that is horizontally disposed when the shell is vertically positioned, and connected pivotally to the shell so as to swing sidewise back and forth between a normal position wherein the frame part overlies the shell and a second position wherein the frame part is disposed at one side of the shell, a roof for the shell located beneath the frame part of the bracket structure and provided with a hole therethrough, means mounted on the bracket structure and arranged and adapted to raise and lower the roof relatively to said frame part and also to connect the roof to the structure so that it swings therewith, an electrode extending normally through the hole in the roof, and means for supporting the electrode carried by said bracket structure and independent of the first mentioned means.

3. An electric arc furnace of the "top charge" variety comprising a tiltable open top shell, a bracket structure pivotally connected to the shell side wall to swing sidewise to and from the latter and having a frame part arranged so that it overlies and is spaced above the shell when the structure is swung toward the shell, a roof

for the shell located beneath the frame part and provided with a hole therethrough, means mounted on the bracket structure, arranged and adapted to raise and lower the roof relatively to said frame part of the structure and also to connect the roof to the structure so that it swings therewith, and including flexible elements depending from the frame part and having the lower ends thereof anchored to the roof, an electrode extending normally through the hole in the roof, and supporting means for the electrode carried by said bracket structure and independent of the first mentioned means.

4. An electric arc furnace of the "top charge" type comprising a tiltable shell, an upstanding shaft positioned outwards of the side wall of the shell and having the lower end thereof fixedly connected to said side wall, a bracket structure comprising an upstanding tubular part mounted rotatably on the upper end of the shaft so that the structure as a whole is capable of swinging laterally to and from the shell, and also comprising a frame part arranged so that it overlies and is spaced above the shell when the structure is swung towards the shell, a roof for the shell located beneath the frame part of the bracket structure and provided with a hole therethrough, means mounted on the bracket structure, arranged and adapted to raise and lower the roof relatively to the structure and also to connect the roof to the structure so that it swings therewith, and including elements depending from the frame part and having the lower ends thereof anchored to the roof, an electrode extending normally through the hole in the roof, and supporting means for the electrode carried by said bracket structure and independent of the roof raising and lowering means.

5. An electric arc furnace of the "top charge" variety comprising a tiltable open top shell, a bracket structure pivotally connected to the shell side wall to swing sidewise to and from the latter and having a frame part arranged so that it overlies and is spaced above the shell when the structure is swung toward the shell, a roof for the shell located beneath the frame part of the bracket structure and provided with a hole therethrough, means mounted on the bracket structure, arranged and adapted to raise and lower the roof relatively to said frame part and also to connect the roof to the structure so that it swings therewith, and including elements depending from the frame part and having the lower ends thereof anchored to the roof, an electrode extending normally through the hole in the roof, supporting means for the electrode carried by said bracket structure and independent of the first mentioned means, and power means between the shell and the bracket structure for swinging the latter to and from the shell.

6. An electric furnace of the "top charge" type comprising a shell, an upstanding shaft positioned outwards of the side wall of the shell and having the lower end thereof fixedly connected to said side wall, a bracket structure comprising an upstanding tubular part mounted rotatably on the upper end of the shaft so that the structure as a whole is capable of swinging laterally to and from the shell, and also comprising a frame part arranged so that it overlies and is spaced above the shell when the structure is swung towards the shell, a roof for the shell, means mounted on the bracket structure, arranged and adapted to raise and lower the roof relatively to the structure and also to connect

the roof to the structure so that it swings therewith, and including elements depending from the frame part and having the lower ends thereof anchored to the roof, and power means between the side wall of the shell and the tubular part of the bracket structure for swinging said structure to and from the shell.

7. An electric arc furnace of the "top charge" variety comprising an open top shell, a bracket structure pivotally connected to the side wall of the shell so as to swing sidewise to and from the latter without vertical displacement relatively to the shell and having a frame part arranged so that it overlies and is spaced above the shell when the structure is swung toward the shell, a roof for the shell located beneath the frame part of the bracket structure and provided with a hole therethrough, means mounted on the bracket structure and arranged and adapted to raise and lower the roof relatively to said frame part and also connect the roof to said structure so that it swings therewith, an electrode extending normally through the hole in the roof and into the shell, and supporting means for the electrode carried by said bracket structure and independent of the first mentioned means.

8. An electric arc furnace of the "top charge" type comprising a tiltable shell, an upstanding shaft positioned outwards of the side wall of the shell and having the lower end thereof fixedly connected to said side wall, a bracket structure comprising an upstanding tubular part mounted on the upper end of the shaft so that it is rotatable relatively thereto without axial displacement and coacting with said upper end of the shaft to support the structure so that it is capable of swinging laterally to and from the shell, and also comprising a frame part arranged so that it overlies and is spaced above the shell when the structure is swung toward the shell, a roof for the shell located beneath the frame part of the bracket structure and provided with a hole therethrough, means mounted on the bracket structure, arranged and adapted to raise and lower the roof relatively to the structure and also connect the roof to said structure so that it swings therewith, and including an element depending from the frame and having the lower end thereof attached to the roof, an electrode extending normally through the hole in the roof and into the shell, and supporting means for the electrode carried by said bracket structure and independent of the roof raising and lowering means.

9. An electric arc furnace of the "top charge" variety comprising a tiltable refractory lined shell, an upstanding shaft positioned directly outwards of the side wall of the shell and having the lower end thereof fixedly connected to said side wall, a bracket structure comprising a normally horizontal arm having a tubular part at one end thereof mounted on the upper end of the shaft so that it is rotatable relatively thereto without axial displacement and coacting with the shaft to support the bracket structure so that it is capable of swinging laterally to and from the shell, and also comprising a frame part connected to, and projecting from, the arm and arranged so that it overlies and is spaced above the shell when the structure is swung towards the shell, a roof for said shell located beneath the frame part of the bracket structure and provided with a hole therethrough, means supported wholly on the bracket structure, arranged and

adapted to raise and lower the roof relatively to the structure and also connect the roof and said structure so that it swings therewith, and including flexible elements depending from the frame part and having the lower ends thereof attached to the roof, an electrode extending normally through the hole in the roof and into the shell, and supporting means for the electrode carried by said bracket structure and independent of the roof raising and lowering means.

10. An electric furnace of the "top charge" variety comprising a shell, an upstanding shaft positioned directly outwards of the side wall of the shell and having the lower end thereof connected fixedly to said side wall, a bracket structure comprising an upstanding tubular part provided with a laterally extending lug and mounted rotatably on the upper end of the shaft so that the structure as a whole is capable of swinging laterally to and from the shell, and also comprising a frame part arranged so that it overlies and is spaced above the shell when the structure is swung towards the shell, a roof for the shell, means mounted wholly on the bracket structure, arranged and adapted to raise and lower the roof relatively to the structure and also connect the roof to the structure so that it swings therewith, and including a flexible element depending from the frame part and having the lower end thereof attached to the roof, and a piston-cylinder device adapted to swing the bracket structure to and from the shell and having one end thereof pivotally connected to said laterally projecting lug on the tubular part.

35 11. An electric furnace of the "top charge" variety comprising a shell having an external laterally extending bracket on the side wall thereof, an upstanding shaft having the lower end thereof fixedly connected to the outer end of the bracket, a bracket structure embodying an upstanding tubular part provided with a laterally extending lug and mounted rotatably on the upper end of the shaft so that the structure as a whole is capable of swinging laterally to and from the shell, and also comprising a frame part arranged so that it overlies and is spaced above the shell when the structure is swung towards the shell, a roof for the shell, means mounted wholly on the bracket structure, arranged and adapted to raise and lower the roof relatively to the structure and also connect the roof to said structure so that it swings therewith, and including flexible elements depending from the frame part and having the lower ends thereof attached to the roof, and a cylinder-piston device adapted to swing the bracket structure to and from the shell and having one end thereof pivotally connected to the laterally extending bracket on the shell and its other end pivotally connected to the laterally extending lug on said tubular part.

12. An electric arc furnace of the "top charge" variety comprising a shell, an upstanding shaft positioned outwards of the side wall of the shell and having the lower end thereof fixedly connected to said side wall, a bracket structure embodying a normally horizontal arm having upstanding slideways mounted on it and embodying at one end thereof an upstanding tubular part mounted on the upper end of the shaft so that it is rotatable relatively thereto and coacting with the shaft to support the structure as a whole so that it is capable of swinging laterally to and from the shell, and also embodying a frame part connected to, and projecting from, the arm and

arranged so that it overlies and is spaced above the shell when the structure is swung towards the shell, a roof for the shell, means mounted on the bracket structure, arranged and adapted to raise and lower the roof relatively to the structure and also connect the roof to the structure so that it swings therewith, and including flexible elements depending from the frame part and having the lower ends thereof anchored to the roof, upstanding electrodes extending slidably through holes in the roof, and upstanding electrode supporting members embodying cantilever type arms with clamps at their outer ends for the electrodes and vertical extensions connected to, and depending from, the inner ends of the arms and mounted slidably in said slideways.

13. An electric arc furnace of the "top charge" variety comprising a tiltable open top shell, a bracket structure connected pivotally to the shell side wall so as to swing sidewise to and from the shell and having a normally horizontal frame part arranged so that it overlies and is spaced above the shell when the structure is swung towards the shell, a roof for the shell located beneath the frame part of the bracket structure and having a hole therethrough, power actuated means mounted wholly on the bracket structure and arranged and adapted to raise and lower the roof relatively to said frame part, and also to connect the roof to the structure so that it swings therewith, an electrode extending normally through the hole in the roof and into the shell, and means for supporting the electrode carried by said bracket structure and independent of said power actuated means.

14. An electric furnace of the "top charge" variety comprising a shell, a bracket structure pivotally connected to the shell side wall to swing laterally to and from the latter and having a frame part arranged so that it overlies, and is spaced above, the shell when the structure is swung towards the shell, and provided with sheaves, a roof for the shell disposed beneath the frame part of the bracket structure, flexible elements trained around the sheaves and having certain ends thereof anchored to the roof, and means on the bracket structure for winding up the flexible elements to effect raising of the roof relatively to the frame part and also paying out the flexible elements in order to effect lowering of the roof relatively to the frame part.

15. An electric furnace of the "top charge" variety comprising a tiltable shell, a bracket structure pivotally connected to the shell side wall to swing laterally to and from the latter and having a frame part arranged so that it overlies, and is spaced above, the shell when the structure is swung towards the shell and provided with sheaves, a roof for the shell disposed beneath the frame part of the bracket structure, flexible elements trained around the sheaves and having certain ends thereof anchored to the roof, and power actuated means on the bracket structure for winding up the flexible elements to effect raising of the roof relatively to the frame part and also paying out the flexible elements in order to effect lowering of the roof relatively to the frame part.

16. An electric furnace of the "top charge" variety comprising a shell, a bracket structure pivotally connected to the shell side wall to swing laterally to and from the latter and having a frame part arranged so that it overlies, and is spaced above, the shell when the structure is

swung towards the shell and provided with sheaves, a roof for the shell disposed beneath the frame part of the bracket structure, flexible elements trained around the sheaves and having certain ends thereof anchored to the roof, and means including a cylinder-piston device on the bracket structure for winding up the flexible elements to effect raising of the roof relatively to the frame part and for paying out said elements in order to effect lowering of the roof structure with respect to said frame part.

17. An electric furnace of the "top charge" variety comprising a shell, a bracket structure connected pivotally to the shell to swing laterally to and from the latter and having a frame part arranged so that it overlies, and is spaced above, the shell when the structure is swung toward the shell and provided with a plurality of sheaves, a roof for the shell disposed under the frame part of the bracket structure, a plurality of flexible elements associated respectively with, and depending from, the sheaves and having the lower ends thereof anchored to the roof and their upper ends extending around and adjustably connected to said sheaves, and power means mounted on the bracket structure and adapted to rotate the sheaves so as to wind up the flexible elements and effect raising of the roof relatively to the frame part and also to rotate the sheaves reversely so as to pay out the flexible elements and effect lowering of the roof with respect to said frame part of the bracket structure.

18. An electric arc furnace of the "top charge" type comprising a tiltable open top shell, an upstanding shaft positioned outwards of the side wall of the shell and having the lower end thereof fixedly connected to said side wall, a bracket structure comprising an upstanding tubular part mounted rotatably on the upper end of the shaft so that the structure as a whole is capable of swinging laterally to and from the shell, and also comprising a frame part arranged so that it overlies and is spaced above the shell when the structure is swung towards the shell, a roof for the shell located beneath the frame part of the bracket structure and provided with a hole therethrough, means mounted on the bracket structure, arranged and adapted to raise and lower the roof relatively to the structure and also to connect the roof to the structure so that it swings therewith, and including elements depending from the frame part and having the lower ends thereof removably connected to the roof, an electrode extending normally through the hole in the roof and into the shell, and supporting means for the electrode carried by said bracket structure and independent of the roof raising and lowering means.

19. An electric arc furnace of the "top charge" type comprising a tiltable shell, an upstanding shaft positioned outwards of the side wall of the shell and having the lower end thereof fixedly connected to said side wall, a bracket structure comprising an upstanding tubular part mounted on the upper end of the shaft so that it is rotatable relatively thereto without axial displacement and coaxing with said upper end of the shaft to support the structure so that it is capable of swinging laterally to and from the shell, and also comprising a frame part arranged so that it overlies and is spaced above the shell when the structure is swung toward the shell, a roof for the shell located beneath the frame part of the bracket structure and provided with a hole therethrough,

means mounted on the bracket structure, arranged and adapted to raise and lower the roof relatively to the structure and also connect the roof to said structure so that it swings therewith, and including an element depending from the frame and having the lower end thereof removably connected to the roof, an electrode extending normally through the hole in the roof and into the shell, and supporting means for the electrode carried by said bracket structure and independent of the roof raising and lowering means.

20. An electric furnace of the "top charge" type comprising a shell, a bracket structure pivotally connected to the shell to swing laterally 15 to and from the latter, having a frame part ar-

ranged so that it overlies and is spaced above the shell when the structure is swung toward the shell, a roof for the shell, means mounted on the bracket structure, arranged and adapted to raise and lower the roof relatively to the structure and also to connect the roof to the structure so that it swings therewith, and including flexible elements depending from the frame part and having the lower ends thereof anchored to the roof, and telescopically connected members between the roof and the frame part for guiding the roof substantially rectilinearly in connection with raising and lowering thereof.
